CLAIM

The ornamental design for planter stand, as shown and described.

DESCRIPTION

FIG. 1 is a perspective view of a planter stand, the light receiving section and the three sets of pot supporting fingers being shown in phantom for illustrative purposes only and forming no part of the claimed design;

FIG. 2 is a front elevational view of FIG. 1, the rear elevational view being a mirror image thereof;

FIG. 3 is a side elevational view, the opposite side view being a mirror image thereof;

FIG. 4 is a top plan view thereof;

FIG. 5 is a bottom plan view thereof;

FIG. 6 is a perspective view of the planter stand, the broken line showing pots, supports and lights is for illustrative purposes only and forms no part of the claimed design; and, FIG. 7 is a perspective view of a second embodiment of the top portion of the planter stand, the lower portion not shown is identical to FIGS. 1-6.
